UNITED STATES PATENT OFFICE

99,985

DESIGN FOR ELASTIC FABRIC OR SIMILAR ARTICLE

Harry Aull, Philadelphia, Pa., assignor to Fried-
berger-Aaron Manufacturing Company, Phila-
delphia, Pa., a corporation of Pennsylvania

Application April 3, 1936, Serial No. 61,936

Term of patent 7 years

To all whom it may concern:

Be it known that I, Harry Aull, a citizen of the United States, residing in Philadelphia, county of Philadelphia, State of Pennsylvania, have invented a new, original, and ornamental Design for Elastic Fabric or Similar Article, of which the following is a specification, reference being had to the accompanying drawing, which forms a part thereof.

The figure is a plan view of an elastic fabric embodying my design as it appears when longitudinally stretched, to a degree substantially equivalent to that incident to normal use. The

figure discloses the elastic fabric enlarged to approximately three times normal size so that it will be approximately twice normal size upon the reduction of the same to the ultimate size as appearing in the patent copy.

I claim:

The ornamental design for elastic fabric or similar article as shown and described.

In testimony of which invention, I have hereunto set my hand, at Philadelphia, Pa., on this 1st day of April, 1936.

HARRY AULL.
